Primary Examiner — Jennifer L Watkins(74) *Attorney, Agent, or Firm* — Workman Nydegger(57) **CLAIM**

The ornamental design for a dial, as shown and described.

DESCRIPTION

FIG. 1 is a perspective view of a dial useable in an anterior component for a cervical collar.

FIG. 2 is a top plan view thereof;

FIG. 3 is a bottom plan view thereof;

FIG. 4 is a first side elevational view thereof;

FIG. 5 is a second side elevational view thereof;

FIG. 6 is a rear elevational view thereof; and,

FIG. 7 is a front elevational view thereof.
